DEVICE FOR SHARPENING RAZOR BLADES

Clarence A. Godshalk, Ardmore, and David Behring, Philadelphia, Pa., assignors to Godshalk Company, a corporation of Pennsylvania

Application March 2, 1932, Serial No. 596,176
Renewed May 8, 1935

7 Claims. (Cl. 51—80)

This invention relates to devices for sharpening razor blades and more particularly to the production of small power driven sharpeners, particularly adapted for home use.

5 The object of this invention is to provide a small machine, the operation of which imposes upon the user a minimum mechanical knowledge, skill or care, and which can be used for sharpening razor blades without actually detaching the 10 blade from the holder of the blade.

A further object of this invention is to provide a razor sharpening device which, upon adjustment, is practically automatic, insofar as the actual dressing of the edge is concerned.

15 A further object of this invention is to provide a device of the character described, wherein are mounted a pair of honing rollers and a pair of stropping rollers, either pair of which, as desired, may be brought into driving relationship with an electric motor by the mere manual movement of a handle on the outside of the device, movable through a definite predetermined path.

20 A further object of this invention is to provide a power driven razor blade dressing device of simple construction, of attractive appearance and of few parts, which are not easily disarranged nor subject to excessive wear nor likelihood of breakage.

25 A further object of this invention is to provide a machine for sharpening razor blades and which is actuated by a small electric motor, the circuit of which is normally broken or open, is closed only when the blade is being sharpened, and is automatically re-opened upon the removal 30 of a blade from the machine.

35 A further object of this invention is to provide a device which is adapted for permanent installation in the bath room of a dwelling in a fixed and convenient position, so that the user may hone or strop a safety razor whenever it is desirable so to do, with a minimum of trouble and without even detaching the blade from the razor or holder.

40 A further object of this invention is to provide a support for the razor blade while it is being sharpened, said support being capable of being accurately adjusted and positioned with respect to the sharpening rollers to adjust the cutting edge of the blade toward and away from the line of the contact of a pair of cooperating blade dressing rollers in order to obtain the best action of the rollers on said cutting edge.

45 A further object of this invention is to provide a safety razor or razor blade holder which when

opened will retain the blade in the holder; which by the act of opening the holder advances the blade forwardly in the holder to a position in which the blade projects sufficiently beyond the holder for insertion between the blade dressing rollers, which coating with the sharpening device, prevents the blade from being drawn by the dressing rollers inwardly beyond a predetermined position, and which, while supporting a blade for sharpening, is pressed against a 10 switch member to close and hold closed, an electric circuit of a motor which rotates the sharpening rollers.

Further objects of this invention will appear in the specification and claims below.

Referring to the drawings forming a part of this specification and in which the same reference characters are used throughout the various views to designate the same parts,

Fig. 1 is a front elevational view of a razor blade 20 sharpening machine embodying this invention;

Fig. 2 is a vertical sectional view on the line 2—2 of Fig. 1, the razor, with the blade retained therein, being shown in elevation and in the position in which it is held while the blade is being 25 sharpened;

Fig. 3 is a side elevational view of the device;

Fig. 4 is a sectionary vertical sectional view of the construction shown in Figs. 1 and 3, showing the lever for oscillating the roller carrying frame 30 and the lever for adjusting the position of the blade supporting guide or bar;

Fig. 5 is a vertical sectional view on the line 5—5 of Fig. 4;

Fig. 6 is a vertical sectional view of the razor on 35 a greatly enlarged scale with the holder in closed position as it is when in use for shaving;

Fig. 7 is a sectional view, similar to Fig. 6 but with the holder open and the blade protruding forwardly;

Fig. 8 is a plan view of the holder with the cover sectioned on the line 8—8; and

Fig. 9 is a front elevational view of the spring plate with the upper part of the razor broken away for the sake of clearness.

45 The improved razor blade sharpening device comprises a casing or housing 1 having a base 2, a front wall 3 having a plane smooth front surface 4, above and to the rear of which is a substantially semicircular chamber or recess 5. To 50 the rear of the wall 3 and under the semicircular chamber 5 is a compartment 6. The sides of the chambers 5 and 6 are preferably closed by side walls 7 and 8, but the rear of the chamber 6 may be and preferably is open. Within the semi-

cylindrical chamber 5 and substantially coincident with the cylindrical axis thereof is journaled a frame supporting shaft 9 for rotation or oscillation. The left-hand end of the shaft 9 5 may be journaled in the side wall 7 in a smooth cylindrical bearing 10, but the right-hand end of the shaft shown in Fig. 1 is preferably journaled in a sleeve 11 which in turn is mounted to rotate in a separable journal box 12 as will be 10 referred to again below.

Upon the shaft 9 is mounted a roller carrying frame 13 the same consisting preferably of two parallel rigid side plates 14 and 15 the ends of which are connected by tie rods or bars 16 which 15 are substantially alike, holding the side plates 14 and 15 in spaced parallel relationship and, together with the side plates, forming a substantial rectangular frame 13, through which extends the frame supporting shaft 9, the frame being rigidly 20 secured to the side shaft 9 to rotate or oscillate therewith, as by set screw 17.

The shaft 9 preferably passes through the frame 13 midway between the ends thereof and preferably substantially midway between the 25 front and rear edges of the side plates 14 and 15 so that the frame and the parts carried thereby are in a substantially balanced symmetrical relationship with respect to the shaft 9.

Mounted for free rotation within the frame 13 30 and on axes substantially parallel to the shaft 9 are two pairs of razor-blade dressing rollers, the term "dressing" being employed herein to define the step of honing and/or stropping. In the preferred construction of this invention there will 35 be employed one pair of honing rollers and one pair of stropping rollers. For convenience, the lower pair of rollers 18, 19 (Figs. 1 and 2) will be considered to be honing rollers and to be provided with a suitable abrasive surface, and the 40 upper pair, 20, 21, will be considered to be stropping rollers and to be provided with a leather or similar surface.

Referring first to the honing rollers 18 and 19, the roller 18 is mounted on a shaft 22 which is 45 journaled in smooth cylindrical bearings 23, 23 in the side plates 14 and 15 respectively, but the other honing roller 19 is preferably mounted on a shaft 24 which is journaled in sliding boxes 25-25 respectively fitting in slots 26 in the side 50 plates 14 and 15 to move toward and away from the axis of the roller 18.

Each sliding box 25 is preferably acted upon by a spring 27 normally to hold the roller 19 yieldingly pressed against the roller 18. The tension 55 of the springs may be varied by the adjusting screws 28. The rollers 18 and 19 are respectively provided with gears 29 and 30 which intermesh to insure the rotation of the rollers 18 and 19 in opposite directions without slippage and at the 60 same angular speed of rotation.

Now referring to the stropping rollers 20 and 21, the roller 20 is mounted upon a shaft 31 which, like the roller 18 is mounted in cylindrical bearings 32-32 in the side plates 14, 15 respectively 65 and the roller 21 is mounted on a shaft in sliding boxes 34, movable in slots 35 toward and away from the roller 20, provided with springs 36 and with adjusting screws 37, like the springs and screws 27 and 28 respectively of the rollers 18 and 19, but tending to hold the roller 21 yieldingly 70 pressed against the roller 20. The roller 20 is also provided with a gear 38 meshing with a gear 39 carried by the roller 21.

The side wall 7 is preferably provided with a bearing 40 for a stud shaft 41, the inner end of

which carries a pinion 42 and the outer end of which is provided with a pulley 43 connected by a belt 44 to the driving pulley 45 of a small electric motor 46, preferably mounted on the base 2. The pair of rollers 18 and 19 are preferably 5 mounted in the roller carrying frame 13 at the same distance from the shaft 9 that the rollers 20-21 are. In other words, the pairs of rollers are symmetrically mounted on diametrically opposite sides of the frame supporting shaft 9 and 10 the shafts of all of the said rollers 19, 20 preferably lie in a plane passing through the axis of the shaft 9.

Also supporting on the frame supporting shaft 9 is a blade supporting and guiding frame 47 consisting of two side plates 48 and 49, the plate 48 lying between the side plate 14 of the frame 13, and the wall 7, and the side plate 49 lying between the side plate 15 of the frame 13, and the side wall 8. The shaft 9 passes through said plates 20 preferably midway between the ends thereof and midway between the front and back edges of the side plates 48 and 49 so that these plates are also 25 symmetrically mounted on the shaft 9. The guiding frame 47 also includes a rigid blade supporting bar 50 rigidly connecting the side plates 48 and 49 at the front lower edges thereof, the same being provided with a slot 51 therethrough in substantially horizontal alinement with the line of the contact of the rollers 18 and 19. A tie rod 30 35 52, on the other side of the rollers 18-19 also rigidly connects together the side plates 48, 49. The opposite edges of the plates 48 and 49 are preferably connected together at the other end of the frame 47 by a blade supporting bar 53, said 40 bar being provided with a slot 54 like the slot 51 of bar 50. The frame 47 also includes a tie rod 55 similar to the tie rod 52. Thus the blade supporting bar 50 is diametrically opposite the blade supporting bar 53 and the tie rod 52 is diametri- 45 cally opposite the tie rod 55.

The side plate 49 may be and preferably is provided with a smooth bearing 56 through which the shaft 9 passes, the blade supporting frame being 50 rotatable with respect to said shaft, but the other side plate 48 is preferably provided with the sleeve 45 57 through which the shaft 9 passes, the sleeve being rotatable in the split bearing or journal box 12.

The free end of the shaft 9 at the right-hand end (see Fig. 4) is provided with a lever 57 rigidly secured thereto in any suitable manner as by the pin 58, and the upper or free end of the lever 57 is preferably provided with a handle 59 having a plunger 60 and a stem 61 terminating in a knob 62 rigidly secured to the stem 61, a spring 63 being provided in the chamber 64 which encircles the stem 61 within the handle and normally presses the plunger 60 against the side wall 8. The side wall 8 is provided with a recess 65 into which the plunger 60 enters and fits when the handle or lever 57 is swung to its vertical position and the said side plate 8 is also provided with a diametrically opposite recess 65' into which the plunger similarly fits when the handle is swung 65 to its lower position. By withdrawing the plunger 60 from either recess 65 or 65' by pulling on the knob 62, the lever 57 is unlocked from its stationary relationship with respect to the casing and may swing through an arc of 180° thus rotating the shaft 9 and the parts carried thereby through a like arc.

The face of the side plate 8 is also preferably provided with an upper stop pin 66 and a lower stop pin 66' adjacent the recesses 65 and 65' re- 70 75

spectively to engage the side of the plunger 60 when it reaches the limit of its swing in either direction.

The sleeve 11 is provided with an adjusting arm 67 rigidly secured thereto by a set screw 68 and the upper end of the arm 67 is provided with a head 69 having a transverse slot 70 therein, and with an adjusting screw 71 extending substantially longitudinally of the slot 70. The screw 71 passes through an end 72 of the head 69 and terminates in a knurled head 73. The said screw 71 passes through a slightly vertically elongated slot 74 in the end 72, so that the free end of the screw is capable of slight movement in a vertical plane. The lever 57 is also provided with a rotatable pin or stud 75 having a head 76 which is provided with a screwthreaded hole extending transversely therethrough and into which the adjusting screw 61 is threaded. The pin or stud 75 is fitted into a cylindrical bearing in the lever 57. The screw 71 is retained in the end 72 of the head by a collar or washer 77 rigidly secured to the screw in any suitable manner.

From the above it will be plain that when the lever 57 is swung from one extreme position to the other, the lever or arm 67 moves therewith because they are connected together by the screw 71 and the pin 75, and that the arm 67 and with it the guiding frame 47 may be moved or rotated through a small angle with respect to the lever 57 and frame 13 by turning the adjusting screw 71. This adjustment of the blade supporting frame 47 with respect to the roller carrying frame 13 is for the purpose of adjusting the blade supporting bars 50 and 53 nearer to or further away from the line of the contact between the pair of rollers 18 and 19 and the pair of rollers 20 and 21 respectively.

In order to permit of this adjustive movement of the frame 47 with respect to the frame 13, the edges of the side plates 14-15 are provided with recesses 78-78 adjacent the guide bars 50 and 53, and with the notches 79 adjacent the tie rods 52 and 55. In order that the pinion 42 may be positioned directly below the frame supporting shaft 13 and that the stud shaft 41 of the said pinion may not interfere with the semicircular movements of the frames 13 and 47 around the axis of the shaft 13, the side plate 14 of the roller carrying frame 13 and the side plate 48 of the blade supporting frame 47 are provided with clearance recesses 80-80 respectively extending above and below the bearing of said side plate 14 on the said shaft 9 deeply enough to permit of the semirotation of the frames and the free adjustive movement of the blade supporting frame 47.

An electric switch 81 is preferably positioned in the compartment 6 under the semicircular chamber 5 and preferably comprises a cylindrical casing 82 of bakelite or other insulating material, the forward end of which is firmly secured in the front wall 3 with its front end preferably flush with the front surface 4. Within the casing 82 is a plunger 83 preferably also of insulating material carrying at its rear end, a metal cap 84 preferably at all times in sliding contact with the stationary contact 85 to which is attached the wire 86 of the motor circuit 86.

Connected to the ring or cap 84 is a stem 87 sliding through the end of the casing 82. Between the said end of the casing 82 and the plunger 83 and surrounding the stem 87, is a spiral spring 88 normally tending to force the plunger to the right (Fig. 2) so that the blade 89 secured

to the forward end of the plunger 83 projects beyond the smooth vertical surface 4 of the vertical wall 3 and so that the end of the stem 87 is clear of and out of engagement with and between the two spring arms 90, forming the stationary electrical contact rigidly secured to the insulation block 91 and connected by the wire 86 to the circuit. The free end of the stem 87 projecting through the end of the casing 82 forms the movable contact point cooperating with the stationary contact 90.

In Figs. 6 to 9 the razor is shown in greater detail than it can be shown in Fig. 2 because they are drawn on a much larger scale.

In order that the sharpening device may be used with a minimum amount of trouble and without even removing the blade from the razor, the razor 92 comprising a handle 93 to the top of which is firmly secured a rigid member 94, preferably composed of a stiff sheet metal stamping comprising in the main a back plate 95, a curved top portion 96, an inner wall 97 and a forwardly extending seat or bottom 98 which is provided with the usual series of slots or cuts 99 at its forward edge and with the downturned lip 100.

The bottom or seat 98 is preferably longitudinally curved or depressed below the side rails or bars 101 but adjacent the inner wall 97 the rails and the portion of the bottom therebetween merge into a curved portion rising slowly above the plane of the upper surface of the side rails and form a flat seat 102. The opposite edges of the rigid member 94 are provided with integral lugs or pins 103, 103 on which the cover or top 104 is pivoted to be swung from an open to a closed position and vice versa.

Located between the bottom or seat 98 and the cover 104 is the blade retainer 105 to the respective ends of which on pivot pins 106-106 are freely pivoted one of the ends of the two like links 107-107, the other ends of which links are pivoted to the cap or cover 104 on pivot pins 108-108 located adjacent the rear lower corners of the lid or cover 104.

The blade retainer 105 is provided at its front edge with an undercut slot 109, extending the full width thereof for the reception of the rear thickened back edge 110' of the otherwise thin blade 110 having a single cutting edge 110''. The back edge 110' of the blade fits into the enlarged undercut portion of the slot 109 and the thin blade itself fits in the narrower front portion and projects outwardly forwardly therefrom. The back edge 110' is longitudinally slid into the said slot 109 for use and may be fixedly held therein by friction or by any other suitable means.

The blade retainer 105 slides forwardly with its ends resting on the side rails 101 as the top 60 is raised to advance the cutting edge 110'' of the blade well beyond the forward edge of the seat or bottom 98 and rearwardly as the top is closed to retract said retainer and blade to a position wherein the cutting edge 110' of the blade also rests on the side rails 101 and over the slots or cuts 99.

As the blade retainer 105 nears the rearmost limit of its said motion, it rides upwardly over the curved portion of the bottom thus tilting the retainer sufficiently to bring the cutting edge 110'' of the blade 110 into contact with the side rails 101 when the blade retainer is on said seat 102. In this position the top or cover 104 is closed and the cutting edge 110'' is firmly pressed against 75

the rails by the forward edge 111 of the cover or top 104.

To permit the links 107 to pass the inner wall 97 as the cover or top 104 is swung on its pivot pins, the side edges of the inner wall 97 are provided with notches or recesses 112-112, a little deeper than the thickness of the links.

To retain the top or closure 104 in its open and in its closed positions, to the back plate 95 is riveted a spring plate 113 having two arms 114 extending from the sides thereof forwardly and upwardly and then laterally and terminating in spring plates 115-115 which respectively lie flat and press firmly against the bottom side edges 116-116 of the top or cap 114 when the cap is in its closed position. When the top is being raised, the spring plates 115-115 are depressed by the curved rear edges 117 of the sides of the cap. Since the side curved edges 117 are in advance of the pivots 103 of the cap when the cap is in its open position, the springs 115 pressing upwardly hold the rear edge 118 of the top of the cap 105 pressed firmly against the upper surface of the curved top 96 of the rigid member 94.

The rear side of the cap 104 is open except as it may be partially closed by the curved top 96 and it is provided with a thumb piece 119 extending rearwardly to enable the user of the razor to open and close the razor by pressing against the said thumb piece. To permit of this movement of the thumb piece the curved top 96 of the rigid member 94 is provided with an ample opening 120.

The spring plate 113 is also provided with an intermediate vertically extending stiff spring 121 terminating in a projecting lip 122 which is held firmly pressed against the lower end of a stiff spring lever 123, said end being held firmly pressed against the front side of the back plate 95 by the resiliency of said spring 121. At the lower end of the lever 123 is a lip or flange 124 making a decided angle with the adjacent portion of said lever, the lip 122 of said spring 121 bearing against said lever 123 or close to said angle. The said spring lever 123 extends upwardly and forwardly and its upper end 125 extends into a slot 126 in the top of the cover 104 a little forward of the rear edge 118. A portion 50 of said lever 123 extends approximately parallel to the inner wall 97, at the rear thereof, and spaced therefrom to yieldingly press against the rear edge of a lug or projection 128 extending rearwardly from the blade retainer 105 through an opening 129 through the wall 97. When the lid or top 104 is closed and the blade retainer is in its rearmost position, the lever 123 is arranged to bear with yielding pressure against the rear end of the lug or projection 128 by reason 55 of the pressure of the lip 122 of the spring 121 on the lip or flange 124 of the rigid lever 123. But the lid being swung to its raised position, the forward end of the spring lever will be swung upwardly, rocking on the outside of the angle 60 made by the lip 124, forcing the spring 121 rearwardly until the lip 122 slides down the flange 124 and presses against the main portion of the lever 123, thus holding the rear edge 118 of the top 104 firmly pressed against the curved portion 65 of the rigid member 94.

This yielding pressure of the lever 123 against the lug 128 when the lid is closed is for the purpose of taking up any looseness or backlash that may exist in the linkages by means of which the 70 blade retainer 105 is connected to the lid or cover

104 and to thus hold the blade fixedly in position when the razor is being used.

In order to sharpen the blade the user first throws the lid or closure of the razor to its upper open position by pressing the thumb piece 119. In so doing, the blade, firmly held in the blade retainer slides forwardly to cause the cutting edge 110' of the blade to project well beyond the flanged end of the bottom 98. If the user wishes to hone the razor, he merely inserts the blade, 10 still held in its blade retainer, into the slot 51 in the supporting bar 50, or if he wishes to strop the razor, he will unlock the reversing lever 57 and rotate it through an angle of 180° to bring the stropping rollers 20 and 21 into the lower 15 position and will insert the blade into the slot 54 or the blade supporting bar 53. In so doing, he will also press the handle 93 of the razor against the flat forward edge of the plate 89, forcing it inwardly until the said edge is flush 20 with the outer surface 4 of the wall 3 thereby closing the contacts 87 and 91 closing the circuit through the motor 46 which immediately rotates the rollers between which the blade 110 is thus inserted.

The tendency of the rollers is to draw the blade inwardly between the rollers, but this is prevented by the forward face of the blade retainer 105 which, bearing squarely against the smooth outer surface of the rigid bars 50 or 53, 30 as the case may be, positively prevents the blade from being pulled inwardly by the rollers beyond a predetermined desired position. The operator is free to slide the razor slightly back and forth laterally over the smooth front surface 4 to 35 change the position of the blade with respect to the rollers and without disengaging the handle 93 from the plate 89 of the plunger 83, thus holding the latter depressed as the handle is slid from side to side over it.

If for any reason it is found that the blade is not properly adjusted with respect to the rollers, the cutting edge may be advanced or retracted by merely turning the knurled head 73 of the adjusting screw 71 to position the bars 50 and 53 45 nearer or closer to the line of contact between the rollers. The adjustment of this screw 71 changing the angle slightly between the adjusting bar or arm 67 and the reversing lever 57 and thus swings the blade supporting frame 47 slightly with respect to the roller carrying frame 13. After having thus dressed the cutting edge of the razor in one or both of the sets of blade dressing rollers as may be found necessary, the operator merely withdraws the blade from the guide bars thereby removing the handle 93 of the razor from the plate 89, whereupon the spring 88 of the switch mechanism throws the plunger 83 and parts carried thereby toward the front of the machine separating the movable contact 47 from 60 the stationary contact 91 breaking the electrical circuit and stopping the motor. There only remains then for the operator to throw the cap or closure 104 to its closed position and the razor 65 is again ready for use.

The construction of the razor is such that it may be easily cleaned without removing the blade from the blade retainer by simply opening the razor and flowing hot water through it.

Nor is there any danger of inadvertently leaving the circuit to the motor closed, for the moment one has finished using it and the handle 93 is removed from its engagement with the edge of the plate 88, the circuit is automatically broken 75

and stays broken until the plate 88 is again depressed.

Having thus described our invention, what we claim and desire to protect by Letters Patent of the United States is:

1. In a razor sharpener, the combination of a housing, a frame supporting shaft mounted to rotate therein, a roller carrying frame rigidly secured to said shaft to rotate therewith, two pairs of blade dressing rollers mounted in said roller carrying frame for rotation on axes parallel to said shaft, said pairs of rollers being mounted on diametrically opposite sides of said supporting shaft and with their axes in a plane coincident with the axis of said supporting shaft, the rollers of each pair of rollers being provided with intermeshing gears to rotate said rollers in opposite angular directions, yielding means to normally hold a roller of each pair of rollers, respectively in contact with the other roller of that pair of rollers, a lever rigidly connected to the end of said shaft to rotate said shaft and said roller carrying frame through an angle of substantially 180°, means to lock said lever to said housing at the limits of its said arcuate movement, a driving shaft also mounted in said housing, a pinion mounted thereon with its teeth in mesh with the teeth of a gear of one of said pairs of rollers when said frame is at one limit of its arcuate movement and with its teeth in mesh with a gear on one roller of the other pair of rollers when said frame is at the other limit of its arcuate movement, and a pair of blade holders cooperating respectively with each pair of rollers.

20

2. In a razor sharpener, the combination of a housing, a frame supporting shaft, a roller frame rigidly secured to said shaft within said housing, a pair of blade dressing rollers mounted in said roller frame to rotate on axes parallel to the axis of said shaft, a pair of intermeshing gears, one gear for each of said rollers to positively rotate said rollers in opposite angular directions at the same peripheral speed, a lever rigid with said shaft, means to lock said lever and said roller frame rigidly with respect to said housing, a drive shaft, a pinion on said drive shaft into mesh with which a gear of one of said rollers moves as it is swung around the axis of said frame supporting shaft, and at the limit of said frame in one direction, and a pair of blade supporting bars each respectively cooperating with one of said pairs of rollers.

35

3. In a razor sharpener, the combination of a housing, a frame supporting shaft, a roller frame rigidly secured to said shaft within said housing, a pair of blade dressing rollers mounted in said roller frame to rotate on axes parallel to the axis of said shaft, a pair of intermeshing gears, one gear for each of said rollers to positively rotate said rollers in opposite angular directions at the same peripheral speed, a lever rigid with said shaft, means to lock said lever and said roller frame rigidly with respect to said housing, a drive shaft, a pinion on said drive shaft into mesh with which a gear of one of said rollers moves as it is swung around the axis of said frame supporting shaft and at the limit of the motion of said frame in one direction, a blade supporting frame also mounted on said frame supporting shaft, a blade supporting bar rigidly carried by said frame, a lever rigid with said blade supporting frame, and means between said levers to adjust the angular relation between said roller supporting frame and said blade sup-

porting frame and to rigidly hold said frames in their adjusted positions.

4. In a device for sharpening a razor blade mounted in a blade holder, the combination of a housing, a pair of blade dressing rollers mounted therein on parallel axes, means to yieldingly hold said rollers normally in contact with each other, gearing between said rollers to drive one from the other in opposite directions, a rigid blade supporting bar in the front of said rollers and provided with a slot through which a blade may be inserted between said rollers, the outer surface of said bar forming a stop surface for engaging said blade holder to limit the distance that the edge of said blade may project inwardly from said bar into engagement with said roller, an electric motor for driving said rollers, a normally open switch in the circuit of said motor and depressed by said blade holder to hold the switch closed so long as said blade is properly held in said slot for sharpening the same.

5. In a device for sharpening a razor blade mounted in a holder having a handle projecting generally below and transverse to the plane of the razor blade, the combination of a housing, a pair of parallel blade dressing rollers normally held in yielding contact with each other, a blade guiding member in front of said rollers having its front face parallel to the axes of contact of said rollers and having a slot therethrough for guiding the cutting edge of a razor blade inserted therein into simultaneous engagement with both of said rollers, said casing being provided with a razor handle guiding surface below, parallel to the front face of, and offset forwardly from the plane of the front surface of said blade guiding member, an electric motor for driving said rollers, and a normally open switch in said housing and having a switch closing member projecting outwardly from said razor handle guiding surface and engaged and depressed to close the circuit to said motor when said switch closing member is pressed flush with said razor handle guiding surface when the handle of said holder is pressed flat against said handle guiding surface.

35

6. In a razor sharpener, the combination of a housing, a frame supporting shaft mounted therein, a roller carrying frame mounted on said shaft, two pairs of blade dressing rollers mounted in said roller carrying frame for rotation on axes parallel to said shaft, said pairs of rollers being mounted on substantially opposite sides of said shaft, yielding means to normally hold a roller of each pair of rollers respectively in contact with the other roller of that pair of rollers, a pair of intermeshing gears for each pair of rollers respectively, a lever mounted on said shaft and rigid with respect to said roller carrying frame to rotate said frame about the axis of said frame supporting shaft, means to lock said lever at the limits of its arcuate movement, a driving shaft also mounted in said housing, a pinion mounted thereon with its teeth in mesh with the teeth of a gear of one of said pairs of rollers when said frame is at one limit of its arcuate movement, and with its teeth in mesh with a gear of the other pair of rollers when said frame is at the other limit of its arcuate movement, a blade supporting frame mounted on said frame supporting shaft, a lever on said shaft rigid with said blade supporting frame and means connecting said levers to adjust the angular relation between said roller supporting frame and said blade supporting frame and

to rigidly hold said frames in their adjusted positions.

7. In a razor sharpener, the combination of a housing, a frame supporting shaft, a roller frame 5 mounted on said shaft, a pair of blade dressing rollers in said roller frame to rotate on axes parallel to the axis of said shaft, a pair of intermeshing gears, one for each roller respectively, a lever mounted on said shaft rigid with respect to said roller frame, means to lock said lever and roller frame rigidly with respect to said housing, 10 a drive shaft mounted in said housing, a pinion on said drive shaft into mesh with which a gear of one of said rollers moves as it is swung by said lever around the axis of said frame supporting shaft to the limit of the motion of said frame in one direction, a blade supporting frame also mounted on said frame supporting shaft, a lever, adjustable on said frame supporting shaft and rigid with said blade supporting frame, and means connecting said levers to adjust said levers and to thereby adjust the angular relation of said blade supporting frame to said roller supporting frame and to rigidly hold said frames in their 10 adjusted positions.
